UNITED STATES PATENT OFFICE

AUGUSTIN GAGNÉ, OF CENTRAL FALLS, RHODE ISLAND, ASSIGNOR TO HEMPHILL COMPANY, OF CENTRAL FALLS, RHODE ISLAND, A CORPORATION OF MASSACHUSETTS

REINFORCING MECHANISM FOR ROTARY KNITTING MACHINES

Application filed August 19, 1922. Serial No. 582,886.

This invention relates to reenforcing mechanism for rotary knitting machines. In order that the principle of the invention may be readily understood, I have disclosed a single embodiment thereof in the accompanying drawings, wherein—

Fig. 1 is an end elevation of a rotary knitting machine having my invention applied thereto;

10 Fig. 2 is a front elevation of said machine having my invention applied thereto;

Fig. 3 is a view similar to Fig. 1, but on a larger scale, of the upper portion of the machine and mechanism adjacent thereto;

15 Fig. 4 is a somewhat diagrammatic view or development from the interior of the needle circle, representing several positions of the reenforcing yarn finger in relation to the needle wave;

20 Fig. 5 is a plan view of the mechanism shown in Figs. 1, 2 and 3;

Fig. 6 is a detail in vertical section upon the line 6—6 of Fig. 5;

Fig. 7 is an end view of the cutter and 25 clamp viewed from the inside of the needle ring;

Fig. 8 is a section upon the line 8—8 of Fig. 5;

30 Fig. 9 is a sectional view similar to Fig. 6, but representing the cutter and binder as open; and

Fig. 10 is a section on the line 10—10 of Fig. 9.

While I have shown my invention as applied to a rotary knitting machine, I desire it to be understood that as to certain features thereof, it is applicable to straight knitting machines. I will describe the invention as applied to a rotary knitting machine of the well known Banner type wherein the needle cylinder rotates and the cam ring is stationary, but it is to be understood that the invention is equally applicable to other types of rotary knitting machines and including types of such machine wherein the needle cylinder is stationary and the cam ring rotates. Moreover, the invention is applicable to knitting machines using either latch needles or spring beard needles. In the present embodiment of the invention, there is disclosed a latch

needle machine having a latch ring functioning as usual in such type of machine, but it is to be understood that in applying the invention to a spring needle machine of the circular type, I use a ring or partial ring instead of a latch ring, but similarly supported and adapted to be tilted out of functioning position, such ring or partial ring carrying the parts of the cutter herein disclosed as carried by the latch ring. In the specification and claims the term "support" is employed in a generic sense as including both a latch ring cooperating with latch needles and a ring or partial ring at or above the circle of spring beard needles.

Referring more particularly to the drawings, the framing of the machine is indicated at 1. It is provided with a table 2 upon which is suitably supported the needle cylinder 3 and adjacent thereto are the usual knitting and other cams for controlling the positions of the needles during both rotary and reciprocating work, since in the present disclosure means are provided for knitting a stocking with heel and toe pockets, the needles being manipulated during the knitting of such pockets by narrowing and widening pickers in a well known manner, not herein necessary to set forth in detail.

Suitably mounted in the framing, is the main drive shaft 4 having thereon the usual pulleys indicated at 5 and also having fast thereon a cam 6, the function of which will be hereinafter set forth. Also mounted in the framing is the usual cam shaft 7 having thereon the usual pattern drums, pattern chains, ratchet wheels and other parts indicated generally at 8, and which, being characteristic of the said Banner machines, need not be described in detail.

The machine is provided with sinkers or web holders of any suitable type and in order to support and operate the same, I provide a sinker cam ring 9 desirably of usual character, surrounding sinkers or web holders of any suitable type and mounted for radial movement in the upper edge of the needle cylinder. These sinkers or web holders are adapted to be moved radially by means of cams of any suitable character. The said

sinker cam ring rests loosely upon or about the upper end of the needle cylinder and is held from rotation with the needle cylinder and its needles and sinkers or web holders in any suitable manner, as, for example, by 5 means of adjustable screws or stops tapped into ears or lugs carried by or formed upon the cam ring. The said ears or lugs are spaced apart somewhat more widely than the width of the post 10 upstanding from the 10 table 2 and having pivoted thereon at 11 the latch or guard ring 12, whereby a certain amount of lost motion is permitted between the needle cylinder and the sinker cam ring so as to permit the proper positioning of the 15 cams of the sinker cam ring with respect to the knitting wave of the knitting needles in a manner not herein necessary more fully to describe.

I provide a suitable number of independently operated pivoted yarn fingers of the general character shown in the patent to Joshua D. Hemphill, No. 934,969, the said yarn fingers including one for the leg of the stocking, another for the high splice and for the reinforcement of the foot, and another for the heel and toe. The said yarn fingers are independently operated from cams upon the cam shaft 7 in a manner characteristic of the said Banner machines, with the exception of the high splice and sole reinforcing yarn finger, which I have indicated at 13, in the several figures, and which in addition to its lowest or operative position 20 and its highest or inoperative position, has an intermediate position which it occupies when inactive during about one half course in each of the courses of the high splice or of the sole reinforcement. To that end, the 25 said high splice yarn guide which is pivoted at 14 upon the latch ring or carrier is acted upon by a lever 15 pivoted at 16 in a post 17 rising from the bed plate 2, the end 18 of said lever being connected by a wire or rod 19 to a lever 20 bearing on a cam upon the cam drum on the cam shaft 7. By the 30 described mechanism the high splice yarn guide is held in elevated or non-functioning position at all times excepting during the formation of the high splice and the foot, and is permitted to drop into its lowest or functioning position during the formation of the high splice and the foot, by the proper positioning of the lever 15 from the said cam 35 upon the cam drum. In order to place the said high splice yarn finger 13 in the said intermediate position, namely, that occupied while inactive during substantially one half the course of a series of courses in the formation 40 of the high splice and foot, I provide a rock shaft 21 mounted in the framing and having a depending arm 22 adapted to bear upon the cam 6, whereby said shaft is rocked at proper times during the formation of the 45 high splice and the foot. Connected to an

arm on the said rock shaft is a rod 23 which is connected to said lever 15 at 23', so that apart from and independently of the means for lifting the high splice yarn finger into its uppermost inactive position, the said yarn finger is lifted into an intermediate position indicated at 13a in Fig. 4, where the feeding end of said high splice yarn finger is above that part of the knitting wave indicated at 24, and is so positioned that the reenforcing 50 yarn 25 pertaining thereto extends to the special cutter and clamp hereinafter described. When the said high splice yarn finger 13 is in its feeding position, it occupies the position shown at 13b in Fig. 4, the regular yarn finger at that time occupying the position indicated at 26 in Fig. 4. When the high splice yarn guide 13 occupies its highest non-functioning position indicated at 13c in Fig. 3, the yarn leads therefrom 55 to the usual clamp and cutter indicated at 27 in Fig. 5. The construction and operation of parts are such that when the high splice yarn finger occupies its highest non-functioning position, the yarn leads therefrom above the needles to the main yarn clamp 27; when it occupies its intermediate position at 13a, the yarn extends above the needles to the special clamp and cutter hereinafter described; and when it occupies its 60 lowest position indicated at 13b, its yarn is being fed to the needles.

The yarn cutter and clamp for the high splice thread and which I have referred to as the special cutter and clamp are preferably mounted upon the latch ring 12 and are shown in detail in Figs. 6 to 10 inclusive. The construction is such that when the latch ring is tilted upon its pivot into inactive position, the cutter and clamp are moved with 65 it as a part of an integral structure and are returned into functioning position with the movement of the latch ring or support into its functioning position. The said cutter and clamp, however, have a movement of 70 their own into and out of functioning position, being lowered into functioning position by means hereinafter described and elevated into non-functioning position. The said cutter and clamp are held in their elevated or 75 non-functioning position with the latch ring down, at all times excepting during the formation of the high splice and the foot, and during the formation of said parts of the stocking, the cutter and clamp are held in 80 their lower or active position, and while so held in their lower or active position are operated twice during each rotation of the needle cylinder, once to open to receive and 85 cut the high splice yarn at the end of the partial course where it is knitted into the fabric, and again to release the yarn from the clamp, so that it may be reintroduced to the needles at the commencement of the next 90 partial course or incorporation of knitting 95

into the fabric. The construction and operation are such that no yarn is lost, since floating yarns are not formed, but the high splice yarn is introduced only for the desired length of the high splice or the sole reenforcement and remains intact from the point where it is cut off to the source of supply.

In order to accomplish the described result, I provide the following mechanism disclosed as one example only of my invention and to which therefore the invention is not limited.

Upon the upper edge of the latch ring 12 I secure the member 28 herein shown as right angled and secured by bolts or screws 29, said member constituting a part of a housing carried by the latch ring, the other part of the housing consisting of the member 30 secured thereto by bolts or screws 31, and receiving between them, and guiding in its movement a slide 32 having a laterally extending pin 32a, to which is connected a coil spring 32b secured to a spring 32c upon the member 28, the construction being such that the slide 32 remains in its lowermost position except when positively lifted. The member 30 is cut away or recessed as indicated most clearly in Fig. 7, so as to receive the slide 32 and the part rigidly attached thereto consisting of a right angled member or piece 33 secured to the slide at 34 and having a head 35 extending substantially vertically downward as indicated clearly in Fig. 7. The said head 35 cooperates with both the clamp and the cutter, which are both vertically movable therewith into elevated or inactive position and into lowered or active position, being pivoted thereto by a bolt 36 having a nut 37 and also a coiled spring 38 to maintain the cutter 39 and the clamp 40 in cutting and clamping relation to the opposite faces of the said head 35.

In order to elevate the slide 32 with the attached parts into inactive position and to hold the said parts in inactive position at all times except during the formation of the high splice and the sole, I preferably provide the following mechanism.

The pivot for the yarn guide is extended as indicated at 41 and carries hubs or sleeves 42, 43 constituting the pivot of a lever 44, one end of which, as indicated at 45 in Fig. 5 and also in Fig. 6, is adapted to take under the horizontally extending portion of the member or piece 33 so as to lift the same vertically, it being guided, as previously stated, in its vertical movements, so that it moves in a right line. The opposite end 46 of the lever 44 has connected thereto a rod 47 downwardly extending to a lever 48 to which it is pivotally connected at 49, the said rod 47 having connected thereto a collar 50 to which is attached a coil spring 51 connected at its outer end to a pin 52 upon the framing, whereby the toe or end 53 of the lever 58 which is pivoted at 54 upon the framing, is

held upon the periphery of a cam disk 55 fast upon the cam shaft 7. The said disk 55 is provided with certain peripheral cams indicated in their approximate positions at 56, 57, the former cam holding the toe 53 of the lever 48 elevated during the formation of the leg and toe and the cam 57 holding said toe 53 elevated during the formation of the heel. During the formation of the high splice the toe 53 rests in the depression 58 and during the formation of the foot the said toe rests in the depression 59. The construction is such that during the formation of the high splice and the sole the special cutter and clamp occupy the position shown in Figs. 6, 7, 8 and 9. At other times the said special cutter and clamp are elevated so that they are entirely out of the way of the other parts of the mechanism.

In order to operate the cutter 39 and the clamp or binder 40, I provide any suitable mechanism, but preferably the following. The member or piece 33 is longitudinally recessed at one face as indicated at 60 in Fig. 8, to receive a horizontally sliding member 61 shown most clearly in Figs. 6, 8 and 10, and having at its outer end a laterally extending pin 62 adapted to be engaged periodically by the face 63 of a lever 64 pivoted at 65 upon a bracket 65a extending from the post 10 and having a bent lower end 66 extending beneath the lower part of the sinker cam ring bed 67, which has thereon at diametrically opposite points the two cams 68 and 69, each of which is adapted to be longitudinally adjusted by means of slots provided therein for the reception of securing screws. When the said lever end 66 engages the cam 68 the clamp or binder 40 is opened to receive the yarn and the cutter 39 is opened to cut the yarn, and when the lever end 66 engages the cam 69, the clamp or binder 40 is opened to release the yarn to permit its reintroduction to the needles for the half course or such other partial course as is requisite for the reenforcement of the high splice and the sole of the foot.

An important feature of my invention resides in the formation of the clamp or binder and its position relative to the cutter. Viewing Fig. 9, it will be evident that the binder or clamp has a substantially right angled open recess 70, wherein the yarn is received for clamping or binding and that the wall or face 71 of such recess is in advance, that is, to the right viewing Fig. 9, of the edge 72 of the cutter, the wall or face 71 and the edge 72 being separated from each other by the thickness of the stationary head 35. In actual construction, the said wall or face 71 is in advance of the cutting edge 72 about three thirty-seconds of an inch, so that when the high splice yarn finger is lifted into its intermediate position shown at 13a in Fig. 4, the high splice yarn is first received in the clamp or binder and then extends across 13b

the edge 72 of the cutter, and as the clamp or binder and cutter are simultaneously moved into clamping and cutting position, the said binder or clamp first becomes effective, because its wall or face 71 is in advance of the cutting edge 72. Thus the yarn is actually clamped against the stationary head 35 before it is severed, and therefore a defect of previous constructions is overcome. In such previous constructions, the yarn was clamped and cut simultaneously with the result that in practice the yarn pulled out of the clamp. By my construction the yarn is effectively held until the clamp is re-opened for the in-feeding of the yarn for the next partial course.

In order to open and close the clamp and cutter, I provide the slide 61 with a transverse pin 73 which moves in an open ended slot 74 in the head 35 and engages notches, one of which is shown at 75, in the upper end of the cutter and the clamp or binder 39, 40. Thus in the to and fro movement of the slide 61, the cutter and the clamp are opened and closed so as alternately to receive and cut the yarn and to release the same.

Having thus described one illustrative embodiment of my invention, I desire it to be understood that although specific terms are employed, they are used in a generic and descriptive sense and not for purposes of limitation, the scope of the invention being set forth in the following claims.

Claims:

1. A rotary knitting machine having a circular series of needles, a pivoted support at the upper end of the needle circle and adapted to be rocked into upper, non-functioning position from its lower, functioning position, one or more regular yarn guides, a reenforcing yarn guide, means to move the latter periodically into inactive position, a housing directly mounted upon said pivoted support, and between the upright spaced walls of which a cutter support is received for up and down movement, a cutter for the reenforcing yarn carried by said cutter support, and means to retain said cutter in lowermost cutting position in said housing when the reenforcing yarn guide is in active position and to elevate it in said housing into an upper, non-cutting position when said reenforcing yarn guide is in inactive position.

2. In a circular knitting machine, a pivoted latch ring or like support, a housing directly mounted upon the upper edge thereof, and having spaced upright walls, a cutter support mounted for up and down movement between said walls, a cutter and a clamp mounted in said housing upon said cutter support and adapted therein to assume a lower active position or an upper inactive position, a yarn guide, means to move the same upwardly into an inactive position, and means whereby the cutter and clamp are

caused to occupy their upper inactive position when said yarn guide occupies its upper inactive position.

3. In a circular knitting machine, a pivoted latch ring or like support, a housing directly mounted upon the upper edge thereof, and having spaced upright walls, a cutter support mounted for up and down movement between said walls, a cutter mounted in said housing upon said cutter support and adapted therein to assume a lower active position or an upper inactive position, a yarn guide, means to move the same upwardly into an inactive position, and means whereby the cutter and clamp are caused to occupy their upper inactive position when said yarn guide occupies its upper inactive position.

4. Reinforcing mechanism for knitting machines including, in combination, a rotary needle cylinder, a stationary cam ring, one or more regular yarn guides, a reenforcing yarn guide, a pivoted latch ring whereon all of said guides are mounted, means to move the reenforcing yarn guide into an upper inactive position, in an intermediate inactive position occupied during partial courses only and in a lowermost or active position occupied during partial courses only, a housing upon the annular portion of the latch ring, comprising spaced upright members, a cutter and clamp support supported therein, an auxiliary cutter and clamp mounted in said housing in said cutter and clamp support for up and down movement, a substantially horizontal plate carried by the latch ring inside the needle circle, a main cutter and clamp directly carried by said plate, and means to move the auxiliary cutter and clamp up and down within said housing in coordination with the movements of the reenforcing yarn guide.

5. A rotary knitting machine having a circular series of needles, a support at the upper end of the needle circle and adapted to be moved into and out of functioning position, a yarn guide, a second yarn guide, means to move the latter periodically into inactive position, a holder upon said support, a cutter carrier mounted in said holder for sliding, right line vertical movement, a cutter supported by said carrier for the second yarn, means to retain said cutter upon said holder in lowermost cutting position when the reenforcing yarn guide is in active position and to slide the said cutter upon its said holder in a vertical right line into an upper non-cutting position when said second yarn guide is in inactive position.

6. A rotary knitting machine having a circular series of needles, a latch ring or like member mounted to be swung into and out of operative relation to the needles, a housing mounted thereon and including two upright spaced parts, a slide received for up and down movement between said parts, a cutter sup-

port carried by said slide and vertically movable therewith in a right line, a cutter mounted on said cutter support and movable therewith in a right line upward into an inoperative position with respect to the needles and downward into operative position with respect to the needles.

7. A rotary knitting machine having a circular series of needles, a latch ring or like member mounted to be swung into and out of operative relation to the needles, a housing mounted thereon and including two upright spaced parts, a slide received for up and down movement between said parts, a cutter support carried by said slide and vertically movable therewith in a right line, a cutter mounted on said cutter support and movable therewith in a right line upward into an inoperative position with respect to the needles and downward into operative position with respect to the needles, and means upon the sinker ring head for operating said cutter.

8. A rotary knitting machine having a circular series of needles, a latch ring or like member mounted to be swung into and out of operative relation to the needles, a housing mounted thereon and including two upright spaced parts, a slide received for up and down movement between said parts, a cutter support carried by said slide and vertically movable therewith in a right line, a cutter mounted on said cutter support and movable therewith in a right line upward into an inoperative position with respect to the needles and downward into operative position with respect to the needles, and means including a lever, and cams upon the sinker cam ring bed for operating said cutter.

9. A rotary knitting machine having a circular series of needles, a latch ring or like member mounted to be swung into and out of operative relation to the needles, a housing mounted thereon and including two upright spaced parts, a slide received for up and down movement between said parts, a cutter support carried by said slide and vertically movable therewith in a right line, a cutter mounted on said cutter support and movable therewith in a right line upward into an inoperative position with respect to the needles and downward into operative position with respect to the needles, a reenforcing yarn guide, means to move said guide into an upper inactive position, an intermediate active position and a lowermost active position in correlation with the movement of said cutter.

10. A rotary knitting machine having a circular series of needles, a latch ring or like member mounted to be swung into and out of operative relation to the needles, a housing mounted thereon and including two upright spaced parts, a slide received for up and down movement between said parts, a cutter support carried by said slide and vertically movable therewith in a right line, a cutter

mounted on said cutter support and movable therewith in a right line upward into an inoperative position with respect to the needles and downward into operative position with respect to the needles, means including a lever, and cams upon the sinker cam ring bed for operating said cutter, a reenforcing yarn guide, means to move said guide into an upper inactive position, an intermediate active position and a lowermost active position in correlation with the movement of said cutter.

11. A rotary knitting machine having a circular series of needles, a latch ring or like member mounted to be swung into and out of operative relation to the needles, a housing mounted thereon and including two upright spaced parts, a slide received for up and down movement between said parts, a cutter support carried by said slide and vertically movable therewith in a right line, a cutter mounted on said cutter support and movable therewith in a right line upward into an inoperative position with respect to the needles and downward into operative position with respect to the needles, and a lever engaging said cutter support to impart the said movement thereto, said lever being adapted to be operated from the pattern drum.

12. A rotary knitting machine having a circular series of needles, a latch ring or like member mounted to be swung into and out of operative relation to the needles, a housing mounted thereon and including two upright spaced parts, a slide received for up and down movement between said parts, a cutter support carried by said slide and vertically movable therewith in a right line, a cutter mounted on said cutter support and movable therewith in a right line upward into an inoperative position with respect to the needles and downward into operative position with respect to the needles, a lever engaging said cutter support to impart the said movement thereto, said lever being adapted to be operated from the pattern drum, and means upon the sinker ring head for operating said cutter.

13. A rotary knitting machine having a circular series of needles, a latch ring or like member mounted to be swung into and out of operative relation to the needles, a housing mounted thereon and including two upright spaced parts, a slide received for up and down movement between said parts, a cutter support carried by said slide and vertically movable therewith in a right line, a cutter mounted on said cutter support and movable therewith in a right line upward into an inoperative position with respect to the needles and downward into operative position with respect to the needles, and a lever engaging said cutter support to impart the said movement thereto, said lever being adapted to be operated from the pattern drum, a reenforcing yarn guide, means to move said guide into an upper inactive position, an intermediate

active position and a lowermost active position in correlation with the movement of said cutter.

In testimony whereof, I have signed my name to this specification.

5**AUGUSTIN GAGNÉ.****10****15****20****25****30****35****40****45****50****55****60****65**
